SEPARABLE BROOCH OR THE LIKE

Adolph Katz, Providence, R. I., assignor to Coro, Inc.,
New York, N. Y., a corporation of New York

Application October 17, 1955, Serial No. 38,393

Term of patent 7 years

(Cl. D45—19)

Fig. 1

Fig. 3

Fig. 1 is a plan view of a separable brooch or the like, showing my new design.

Fig. 2 is an edge view thereof.

Fig. 3 is a plan view of the brooch in separate positions.

I claim:

The ornamental design for a separable brooch or the like, substantially as shown.
